UNITED STATES PATENT OFFICE.

ENGELBERT BREHER, OF CHASKA, MINNESOTA.

WATER-CLOSET-SEAT PROTECTOR.

SPECIFICATION forming part of Letters Patent No. 396,803, dated January 29, 1889.

Application filed October 18, 1888. Serial No. 288,500. (No model.)

To all whom it may concern:

Be it known that I, ENGELBERT BREHER, a citizen of the United States, and a resident of Chaska, in the county of Carver and State of Minnesota, have invented certain new and useful Improvements in Water-Closet-Seat Protectors; and I do hereby declare the following to be a full, clear, and exact description of the same, reference being had to the accompanying drawings, forming a part of this specification, and to the figures and letters of reference marked thereon.

This invention relates to that class of sanitary articles employed as temporary coverings for the seats of water-closets and designed to prevent contact of the person with the surface of the permanent seat, whereby the person of the occupant is protected from contamination by filth and infectious diseases—such as are liable to be contracted at public resorts; and it consists in the improved combination and arrangement of parts, hereinafter described and claimed, to form a cheap and simple portable protector, which can be folded into a small compass and adjusted to accommodate the size of the opening in the permanent seat or the posterior dimensions of the individual.

In the accompanying drawings, Figure 1 is a top plan view showing my improved protector open and in dotted lines expanded. Fig. 2 is a view in perspective showing the sections partially folded. Fig. 3 is a detail view of the hinge detached. Fig. 4 illustrates a modified form of hinge.

Similar letters of reference in the several figures indicate the same parts.

The protector is formed in two sections, A A', each composed of two or more segmental pieces, *a a'*, of wood or other material, hinged together, as indicated at *l*, so as to be capable of folding the one upon the other, as indicated in Fig. 2. The pieces *a a'* are cut or formed in corresponding arcs, so that when folded or assembled together they will assume the form of a package equal in length and width to one of the segments and in thickness to the aggregate of all the sections. The inner ends of the corresponding segmental pieces *a* of the two sections A A' are joined together by hinge B, whose two leaves, *b*, are

so attached or connected to the segments *a* as to permit both longitudinal and lateral adjustment of the sections A A', whereby the interior dimensions of the opening encircled or surrounded by the sections A A' can be increased or diminished, and at the same time the folding of the inner segments, *a*, is permitted. One mode of accomplishing this purpose is illustrated in the drawings, (though, as is obvious, other equivalent means might be employed,) consisting in providing the leaves *b* with arc-shaped slots *b'* and the segments *a* with slots *a'*, for the reception of said leaves, pins *a*³, passing through the slots *b'*, serving to hold the leaves in the slots *a'* and serving as pivotal points about which the sections A A' can be swung. The proximate ends of the leaves are jointed to an interposed connection, A², so that one section, *a*, can be folded upon the other, this interposed link or connection A² accommodating the thickness of the walls of slots *a'*.

The operation of my improved cover will be readily understood. For packing and transportation the segments are folded together, as indicated in Fig. 2, forming a package occupying the minimum space with the several parts permanently secured together, so that they cannot be accidentally separated or misplaced, and are always in condition for immediate service. In applying the cover, the several segments are unfolded and extended, after which the sections are adjusted by drawing the segments *a* more or less apart and swinging the segments *a'* toward each other until the opening in the permanent seat is entirely covered or reduced to the desired dimensions.

When employed for the accommodation of very small children or infants, the front end of one section can be drawn so as to overlap the other, thereby materially reducing the size of the opening.

In the modification shown in Fig. 4 the form of the connecting-hinge is departed from somewhat. The leaves of the hinge, which in this instance are preferably round rods, are simply slipped into sockets in the sections, thus being permitted only a sliding movement on the leaves. In order now to provide for the pivotal movement of the sections in a hori-

zontal plane, the ends of the leaves are loosely connected together—as, for instance, by a ring, A², on which they may have a sliding movement. An arrangement such as indicated in 5 Figs. 1 and 2 is, however, preferred, as furnishing a more rigid connection for holding the sections A A' in substantially the same plane.

Having thus described my invention, what I 10 claim as new is—

1. In an adjustable cover such as described, the combination, with the sections A A', of a hinge connecting their proximate ends and a movable pivotal connection between the 15 leaves of the hinge and sections, whereby the sections may be moved longitudinally of the leaves and swung thereon to vary the size of the opening, substantially as described.

2. In an adjustable cover such as described, 20 the combination, with the arc-shaped sections A A', of a hinge having the arc-shaped leaves and adjustable connections between said leaves and the arc-shaped sections, whereby they may be adjusted in the direction of their 25 arcs, substantially as described.

3. In a portable and adjustable cover such as described, the combination, with the sections A A', having the slots or sockets in their ends, of the adjustable connection consisting 30 of a hinge, the leaves whereof are each pivoted and movably secured within the sockets in the ends of the sections to permit of the longitudinal and lateral adjustment of the sections, substantially as described.

35 4. The combination to form a portable cover such as described, of the two sections A A'

and an interposed connection, A², uniting the ends of the sections, comprising two leaves hinged together and provided with slots, each of said slotted leaves being attached to the 40 end of one of the sections by a pin, whereby the sections are permitted a longitudinal and lateral movement, as set forth.

5. In an adjustable cover such as described, the combination, with the two sections A A', 45 each composed of the hinged sections a a', of the hinge having the two leaves and adjustable connections between the leaves and sections A A', substantially as and for the purpose specified.

6. In combination with the arc-shaped sections A A', each formed of two segments hinged together to fold flat, a hinge having the intermediate connecting-link, A², interposed between and connecting the proximate 55 ends of said sections, as and for the purpose set forth.

7. In a portable cover such as described, the combination, with the folding sections A A', 60 each provided with a slot, as at a², of the hinge-connection A², consisting of two leaves hinged to an intervening link, and each formed with a slot, said leaves being received in the slots in the ends of the sections and held therein by pins passing through the slots, as and for 65 the purpose specified.

In testimony whereof I have hereunto set my hand in presence of two subscribing witnesses.

ENGELBERT BREHER.
